ATYS.

UNITED STATES PATENT OFFICE

HERMAN L. STRONGSEN, OF NEW YORK, N. Y.

MOTH EXTERMINATOR

Application filed May 18, 1932. Serial No. 612,130.

This invention relates to moth exterminators.

One of the objects of the invention lies in the provision of a ball type moth exterminator, the same comprising a base portion containing a solidified chemical and a detachable apertured cover and an electric heating element disposed within the the container in a manner to liquefy the chemical, whereupon a vapor fatal to moths escapes from the apertures.

Another object lies in the provision of a moth exterminator of a ball type, the same containing a solidified chemical adapted to be liquefied by a heating element, the escaping vapors being fatal to moths, said container being further so fashioned as to automatically seat itself in an upright position, irrespective of the position in which same is placed.

Other objects will appear in the following specification taken in connection with the annexed drawing, in which—

Fig. 1 is a plan view of my ball shaped moth exterminator;

Fig. 2 is an elevational view thereof;

Fig. 3 is a cross-sectional view on line 3—3 of Fig. 1;

Fig. 4 is a cross-sectional view taken on the line 4—4 of Fig. 3.

Before referring specifically to the drawing, it might be stated that the method employed in the present application for the extermination of insects, including especially moths, has been described and claimed in my copending application, Ser. No. 533,840, filed April 29, 1931.

The present application is directed to a specially formed ball shaped container, which may be readily handled by the operator and placed in operative position in closets, beneath furniture and generally in more remote positions than can ordinarily be obtained by moth exterminators having a more conventional shape.

Referring specifically to the drawing, it is found that the container is rounded or shaped in the form of a ball. The base portion of the container, designated 10, is adapted to receive a quantity of solidified chemical 11,

details of which have been described in detail in my above referred to pending application. This chemical, when in a cool state, becomes a solid; however, when liquefied by the presence of heat, the chemical gives off a vapor which is fatal to insects and especially moths.

The upper portion of the ball has been designated 12, the same being rounded in form and detachably connected to the base by means of the co-operating detachable connecting means 13 on the cover and 14 on the base respectively.

Obviously, this connection between the cover and base of the ball might be accomplished in numerous ways and this manner of connection has merely been shown for the purpose of showing that the cover may be detached from the base by simple manual operation which is necessary for replenishing the base with a new chemical when the original supply has been exhausted.

The cover member is apertured as at 15 in a manner to permit escape of the vapors.

Means for liquefying the solidified chemical 11 is found in the electric element of a resistance type, the same being described generally as 16. It is quite obvious that this resistance or heating element might be made in various forms, it being merely essential that same be disposed within the container in such position that the heat therefrom will liquefy the solidified chemical 11.

It may be explained that no vapor escapes from the chemical 11 when in the solidified form.

Current is supplied to the electric connection through the electric cord 17, this cord operating not only to supply electric current to the heating element, but also as a suspension and supporting means for the container as a whole. Conventional insulating means for the cord is shown at 18.

With respect to the operation of the device, it is apparent that same may be transported by the operator by merely grasping the cord 17. This provides convenient transportation and supporting means for the ball. The cord 17 normally is of sufficient length that the ball may be placed or rolled to a

position desired at a considerable distance from the current socket.

As far as the shape of the container is concerned, it will be noted that same has a flattened base portion 19 which, operating in connection with the ball shaped container, automatically acts to seat the container in an upright position, irrespective of the position in which the ball is placed or rolled.

It will be noted that by fashioning the base portion in this manner, the cord may be grasped in one hand and the ball manually rolled to a position beneath the furniture, whereupon the ball will automatically seat itself in an upright position. By such fashioning of the ball, the same may be disposed in remote places where the placement thereof may be difficult, or further it might be rolled into such remote positions that might otherwise not be reached.

Assuming that the ball has reached the desired place and has assumed an upright position, the operator then merely connects plug 20 in the conventional current socket, whereupon the electric heating element 16 becomes heated and liquefies the solidified chemical 11. The liquefaction of the chemical 11 results in the escape of vapors through the apertures 15, which vapors when coming in contact with the fabric material, irrespective of its character, forms a coating thereon, which absolutely exterminates moths, larvae or eggs.

When applicant's device has served its purpose of killing the moths, obviously it is simple to break the electric current by pulling out the plug 20 and thereafter either placing or rolling the ball into a different place or position.

What I claim is:

1. A portable moth exterminator comprising a container having a base portion adapted to contain a solidified moth-exterminating chemical, and a cover member for said base adapted to protect the chemical from displacement and accidental disturbances, said cover member being provided with restricted apertures for discharging vapors from said container, an electrical heating element mounted within and surrounded by said cover member so as to be protected thereby, said heating element being located, when the cover is closed, adjacent to said chemical whereby the chemical is heated and converted from a solid to a liquid state and a detachable connection between the base portion and the cover member at a substantially intermediate point, said detachable connection permitting ready removal of the cover member to permit the insertion of the solidified chemical within the base.

2. A portable moth exterminator comprising a container having a base portion adapted to contain a solidified moth-exterminating chemical, and a dome-shaped cover member

for said base adapted to protect the chemical from displacement and accidental disturbances, said cover member being provided with a restricted opening for discharging vapors from said container, an electrical heating element mounted wholly within and surrounded by said cover member so as to be protected thereby, said heating element being located, when the cover is closed, adjacent to but out of contact with the exposed surface of said chemical, whereby the chemical is heated and converted from a solid to a vapor state, and a detachable connection between the base portion and the cover member at a substantially intermediate point so that the base member and cover member form complementary shells of approximately equal volumes, said detachable connection permitting ready removal of the cover to permit the insertion of the solidified chemical within the base.

In testimony whereof I have hereunto affixed my signature.

HERMAN L. STRONGSEN.
